UNITED STATES PATENT OFFICE

2,439,143

TOY HELICOPTER

Stephan Paul Nemeth, Chicago, Ill.

Application March 7, 1944, Serial No. 525,404

4 Claims. (Cl. 46—75)

1

This invention relates to a toy helicopter. The invented article is an inexpensive stable toy helicopter, one which preserves the horizontal direction of its fuselage and the vertical position of its mast, executes a steady forward motion, and lands gently. The toy does all this without requiring complicated mechanisms or precision parts which could not be manufactured inexpensively.

This is accomplished by stabilizing and dampening a one-piece sustaining propeller by a counter-rotating dampening and stabilizing vane member, the vanes being of special shape. I have discovered that counter-rotating pronouncedly angularly bent vanes, mounted in proper position, impart stability and steadiness of flight to a toy helicopter which without such vanes flies in an unstable and unsteady manner.

It is thus the object of the present invention to provide a toy helicopter sustained by a driven one-piece propeller and stabilized by counter-rotating vanes of particular shape and position.

These and other desirable objects and advantages of the present invention will be illustrated in the accompanying drawings and described in the specification, a certain preferred embodiment of the invention being disclosed by way of illustration only, for, since the underlying principles may be incorporated in other specific devices it is not intended to be limited to the one here shown, except as such limitations are clearly imposed by the appended claims.

In the drawings like numerals refer to similar parts throughout the several views, of which

Fig. 1 represents a toy helicopter in plan view,

Fig. 2 represents the same helicopter in elevation, partly in section, and

Fig. 3 represents an elevational section through the lower end of the mast.

The toy helicopter represented in the drawings consists of a body or fuselage 11, a mast or standard 12, a rotor or sustaining propeller 13, counter-rotating vane arms 16 holding stabilizing vanes 17, and motor means 15 arranged to drive the propeller relative to the vane arms.

Body 11 is preferably made of a stiff paper, bent and joined to any shape suggesting the fuselage of a helicopter. It is contemplated but not shown in the drawing that the paper forming the fuselage will be decorated to carry the suggestion to greater length, windows, a door and wheels being printed on the same to enhance the similarity with an actual fuselage. The two sides of the fuselage are stiffened by a bridge member 22.

2

The upwardly extending mast 12 is formed of a tube, for instance a paper tube or a light wooden tube. The mast 12 extends through suitable perforations of the body, wide enough to permit easy rotation of the body relative to and around the mast. During the flight, the weight of the body rests on the washer 21 of the mast. Pin 20 penetrates the mast crosswise, near its lower end, and washer 21 rests against pin 20.

Propeller 13 is preferably bent of one piece of Celluloid sheeting. It is mounted rotatably on top of the mast, the axis of rotation coinciding with the mast axis. Part 14, fixed to the propeller, combines the functions of a clamp holding the propeller, of a shaft, driving the propeller, of a journal revolving in the top portion of the mast, the same acting as a bearing, and of a hook receiving the driving means.

A rubber band 15 within the hollow mast is fastened at its lower end to the mast, being slung around pin 20. At its upper end it is fastened to said hook 14, and thus mediately to the propeller. It constitutes in a well known manner a motor for driving the propeller 13 and the mast 12 in opposite directions.

Vanes 17 are each made of a rectangular piece of stiff paper. The paper is bent to a pronounced dihedral angle about the edge 19 parallel to and midway between two parallel sides of the rectangle. The vanes have thus the shape of a stiff book cover being partly opened, or of a plain gable roof.

A rod 16 extending crosswise to the mast is fastened thereto. The angularly bent vanes 17 are punched at two points 18 on both sides of the edge 19, and are mounted on the two ends of rod 16. The rod passes through the holes 18 and the vanes are glued to the rod.

The vanes are mounted on the rod in such angular position that edge 19 extends at right angles to the rod 16 and is inclined relative to the plane of its motion. The toy is illustrated in the drawing as provided with a right hand propeller. The propeller is turned by the rubber motor in flight 45 anti-clockwise as seen from top. The arms 16 with the vanes 17 will then be turned clockwise as seen from above. When thus rotating, edges 19 are in forward relation to the vanes 17. Thus, in Fig. 1, the vanes 17 as drawn indicate the direction of rotation of the vane arm 16 as if they represented arrow heads. Edge 19 is accordingly inclined upwardly and in the direction of its own turning motion.

The vanes are thus similar and in similar arrangement and motion as airfoils having a very

pronounced dihedral and having a positive angle of attack or incidence. I have obtained the best results by folding the vanes to a dihedral about edge 19 of about 90 degrees, and by inclining edge 19 upwardly and in the direction of their rotation by 30 degrees to 45 degrees.

When playing with the toy helicopter, the lower part of the mast is held by one hand, the propeller is wound clockwise by the other hand, and the toy is released with its mast vertical. It will gently soar upwardly and will return to the ground as the tension of the rubber band decreases, having enough parachute effect and residual motor effect to protect the toy from excessive shocks when making contact with the ground.

I claim:

1. In a toy helicopter the combination of a sustaining propeller and of at least one counter-rotating vane below the propeller made of two plane surfaces forming a dihedral angle and, the vane being set to positive dihedral and to positive incidence angle.

2. A toy helicopter having a mast, a one-piece sustaining propeller mounted rotatably on top of said mast, vane members each made of two plane surfaces forming a dihedral angle and fastened to the mast, motor means adapted and arranged to rotate the mast and the propeller in opposite directions, and a fuselage supported by and freely rotatable about the mast.

3. A toy helicopter having a mast, a sustaining propeller mounted rotatably on top of the

5 mast, vanes each made of two plane surfaces forming a dihedral angle and connected to the mast, motor means adapted and arranged to rotate the mast and the propeller in opposite directions, and a fuselage supported by and freely rotatable about the mast, said vanes being mounted to positive and pronounced dihedral and to positive incidence angle.

4. A toy helicopter having a hollow mast, a 10 sustaining propeller mounted on top of the mast rotatable thereabout, vanes each made of two plane surfaces forming a dihedral angle and connected to the mast, a rubber cord within the mast connecting the propeller with a point of 15 the mast near its bottom end, a fuselage supported by and freely rotatable about the mast, torque transmitting means between the rubber cord and the mast, and torque transmitting means between the rubber cord and the propeller.

20 25 STEPHAN PAUL NEMETH.
